UNITED STATES PATENT OFFICE.

JOHN K. ROGERS, OF BROOKLINE, MASSACHUSETTS.

DESIGN FOR PRINTING-TYPE.

SPECIFICATION forming part of Design No. 15,080, dated June 17, 1884.

Application filed January 6, 1883. Term of patent 7 years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the accompanying impression is an exact representation, and is a part of this specification--impression marked (C)

What I claim as my invention, and desire to secure by Letters Patent, is--

The design for printing-types, as shown in the accompanying impression.

JOHN K. ROGERS.
